UNITED STATES PATENT OFFICE.

CHARLES A. LUNDGREN, OF DETROIT, MICHIGAN, ASSIGNOR TO BURROUGHS ADDING MACHINE COMPANY, OF DETROIT, MICHIGAN, A CORPORATION OF MICHIGAN.

ADDING AND LISTING MACHINE.

1,195,599.

Specification of Letters Patent. Patented Aug. 22, 1916.

Application filed September 4, 1914. Serial No. 860,292.

To all whom it may concern:

Be it known that I, CHARLES A. LUNDGREN, a citizen of the United States, residing at Detroit, in the county of Wayne and State of Michigan, have invented certain new and useful Improvements in Adding and Listing Machines, of which the following is a specification.

The present invention relates to so-called tally-roll attachments or equipments for adding and listing machines and is in the nature of an improvement upon the invention of Fred F. Main which has been made the subject of a prior patent issued January 5, 1915, No. 1,123,337.

One object of the present invention is to do away with a tally-roll carriage construction which requires parts extending laterally beyond the machine proper to unite the supports for the supply and take-up rolls for the tally strip. Thus according to my invention the upper and lower roll holders are connected by and unified with a portion of the carriage extending directly between them, this portion of the carriage being of such character as to be accommodated in the limited space between the main paper carriage structure and the back of the machine proper, while at the same time being of such character as to supply an effective guide or chute for the strip.

Another object of the invention is to provide improved facilities for use of the tally-roll equipment at the will of the operator without regard to any predetermined relation between the same and the tabulating equipment for regulating the lateral shifting of the main carriage manually or in an automatic manner. At the same time I prefer to serve the capacity of the tally-roll equipment for automatic coöperation with such tabulating equipment.

With these and incidental objects in view the invention consists in certain novel features of construction and combinations of parts, the essential elements whereof are recited in the appended claims and the preferred form of embodiment of which is illustrated in the accompanying drawings, which form a part of this specification.

Of such drawings Figure 1 represents in right side elevation an adding and listing machine of the well-known Burroughs type having added thereto a tally-roll equip-

ment embodying my present invention; Fig. 2 is a broken out rear elevation of the machine with the tally-roll in non-printing position; Fig. 3 is a rear elevation with the regular carriage equipment omitted and the tally roll in printing position; Fig. 4 is a vertical section on line 4—4 of Fig. 3; Fig. 5 is a partial top plan view of the machine with the tally-roll carriage in section and the regular paper carriage equipment omitted; Fig. 6 is a vertical section of the lower rear portion of the machine taken substantially on the line 6—6 of Fig. 2; Fig. 7 is a detail sectional view taken on the line 7—7 of Fig. 2; Fig. 8 is a fragmentary rear elevation of the same parts under a different adjustment with certain of them in section on line 8 of Fig. 1; Fig. 9 is a horizontal section taken substantially on line 9—9 of Fig. 2; Fig. 10 is a broken sectional rear elevation illustrating one printing position of the tally-roll strip with relation to the main paper carriage and as brought about through coöperation with the tabulating equipment for said main paper carriage. Fig. 11 is a similar view illustrating a different printing position of the tally strip as related to the main paper carriage and as brought about through similar coöperation of parts; Fig. 12 is a detail illustrating operation of certain parts upon return of the main carriage from the position illustrated in Fig. 11.

The machine proper requires no description, being thoroughly familiar to those skilled in the art, through extensive commercial use besides which numerous patents have issued disclosing it in all of its details. Reference may be had in particular to certain of these prior patents which show various paper carriage equipments as applied to this type of machine and bearing more or less similarity to the equipment here shown and with which the tally-roll equipment of my invention coöperates. In this connection attention is invited to Patent No. 913,738 dated March 2, 1909; Patent No. 924,118 dated June 8, 1909; Patent No. 929,056, dated July 27, 1909, and Patent No. 977,582 dated December 6, 1910.

Numeral 618 designates type plates such as commonly employed in Burroughs machines and the reference numeral 17 designates a roller platen against which these type

plates are driven, said platen being mounted as usual in a cradle 18 mounted upon a carriage 19 which travels across the back of the machine upon a track 20. The cradle 5 is here shown as carrying a holder 21 designed for receiving ledger sheets in flat form which when dropped into this holder will enter the bite between the roller platen and the pressure roller 22 (Fig. 4) so as to 10 be properly fed upon the turning of the roller platen. The tally roll equipment is particularly useful in connection with ledger work and this type of holder has been specially designed for the purpose of handling 15 ledger sheets in the flat form, though it forms no part of my invention.

The tally-roll carriage of my present invention comprises a slide rod 30 which runs through lugs 31 (Fig. 2) on the base of the 20 machine proper and interposed lugs 32 on the back panel of the machine, the rod thus taking the place of hinge pintles ordinarily occupying the perforations of these lugs. This arrangement provides for minimizing 25 the amount of projection of the tally-roll equipment at the rear of the machine. The tally-roll carriage further comprises lower side plates 33 and 34 having bosses embracing the said rod 30 and fastened thereto by 30 set screws, said plates supporting between them the journal rod 35 of a take-up roller 36 for the tally-roll strip. A vertical plate 37 unites the plates 33 and 34 at their upper front portions and extends rearwardly 35 between the plates on a downward inclination to the under side of the take-up roller 36, as shown in Fig. 4, this portion 37^a of the plate supplying a table over which the tally strip 40 passes. The said plate 37 extends 40 upwardly along the back panel 2 of the machine through a space between the same and the carriage track 20 and carriage 19 and thence on up with a slight forward bend in front of the roller platen where it 45 is curved in general conformity therewith and made with an opening 37^b through which the tally-roll strip 40 passes from the front to the rear side of the plate, as clearly illustrated in Fig. 4, the type 618 being 50 adapted to strike through said opening when the tally strip is in position to be printed upon. A second vertical plate 38 slightly spaced from the plate 37 and united therewith at the sides, forms with said plate 55 37 a flattened tube supplying a chute or guideway for said tally-strip in its passage downward from the roller platen. It will be noted that the tally strip is in this manner completely enveloped by the metal of 60 the tally-roll carriage in a space between the back panel of the machine and the main carriage track and carriage, so that said strip is thoroughly protected and extensively guided where it runs in close proximity to parts of the machine with relation

to which it shifts and there is therefore no opportunity for said strip becoming crumpled or torn through encounter with such parts of the machine proper during the lateral shift of the tally-roll carriage or 70 the main carriage. At the same time it will be noted that the tubular construction increases the rigidity of this portion of the tally-roll which connects the take-up roll holder and the supply roll holder. The latter located above the roller platen is composed of side plates 37^c which may consist of bent-over portions of the same plate which supplies the before mentioned open-center curved portion 37^b. Thus this plate extends 75 vertically from the curved portion as at 37^d and the arms 37^e are bent forward and support between them the rod or pin 39 on which the tally-supply roll 40^a is mounted. In order to properly guide the 80 tally strip from this roll down to the roller platen and guard it from being interfered with by any portion of the machine proper, there is fastened to the supply roll holder a plate 41 inclined with relation to the plate 85 portion 37^d and having bent-over side pieces 41^a screwed to the arms 37^e,—a tapering chute being thus supplied for the tally strip to pass through. The plate 41 terminates 90 at the lower end just above the plate opening 37^b before mentioned, and serves to guide the strip easily into this opening. The tapered form of the above described 95 chute facilitates the threading of the strip therethrough when the tally-roll is initially 100 arranged for use. To further facilitate introduction of the strip through its various guides I prefer to make the opening 37^b uninclosed at one side as shown in Fig. 3. In addition to this the plate 38 is cut out in 105 the center, as also shown in Fig. 3, so that access may be had to the strip at this lower point if need be for working it down through the lower chute.

It is desirable to make the tally-roll carriage as light as consistent with the necessary stability and it will be noted that I employ relatively thin metal plate in its makeup and keep down the width of the structure to approximately that of the strip 115 itself throughout the major portion. The opening 37^b must of course be as wide as the strip and here I provide a connecting offset plate portion 37^e which may be reinforced 120 by a rib or strip 37^f.

It will be seen that the above described construction of tally-roll carriage fulfills one of the objects primarily stated, having reference to the avoidance of parts protruding laterally beyond the machine proper for 125 connecting upper and lower portions of the tally-roll carriage, while at the same time a thoroughly rigid construction is provided so that the tally strip is kept in proper alignment; besides which it is so guided and 130

guarded that it cannot be interfered with by parts of the machine proper relative to which the tally-roll carriage shifts.

There is preferably mounted in the upper or supply roll holder a pressure finger 50 to bear against the supply roll with enough friction to keep the strip taut as it is pulled from the roll. Said finger is secured to a rock rod 51 journaled between the arms 37^c and is pressed against the roll by a spring 52, Fig. 3. A guiding roller 60 is journaled between the side plates 33 and 34 of the take-up roll holder in the corner where plate 37 and table 37^a meet (Fig. 4) and the strip passes down in front of this roller and underneath it and thence on to said table.

A pressure roller 61 bears against the take-up roller 36 being mounted upon a journal rod 62 which occupies open slots in the said plates 33 and 34 and is supported by a pair of arms or levers 63 bifurcated at their rear ends to engage pivot studs 64 on the said plates, and connected at their rear ends by springs 65 with other studs 66 on said plate. As a convenient means for taking the pressure off, if it should be desired to run the strip backward, I mount in said plates a rock rod 68 having flattened portions forming the bases of slots normally occupied by the aforesaid arms or levers 63. A handle 69 is fastened to one end of said rock rod and it will be obvious that by turning this handle the pressure roller may be forced out of engagement with the take-up roller 36. Between portions of the plates 33 and 34 which extend in rear of the said roller, a plate 70 is secured having a serrated edge by which the strip may be severed at will after passing out under this plate and over the rod 68, from between the take-up roller and the pressure roller.

A spring 80 connected at one end to one of the lugs 32 and at the other end to the set screw of the boss of the aforesaid plate 33 tends to hold the tally-roll carriage to the right in non-printing position. This position is determined by the abutment against one of the lugs 31 of a leather washer 81 backed up by a collar 82 which is secured to the rod 30. The lower portion of the plate 34 is preferably offset from the main portion (see Figs. 10 and 11) so that the said washer may be substantially flush with the main portion of the plate and a non-printing position of the tally-roll carriage farther over to the right thereby provided for. The printing position of the said tally-roll carriage is determined by abutment of a similar washer 85 (Fig. 3) against the side of an arm 86 secured to one of the lugs 31, said washer being backed up by a sleeve 87 on the righthand end of the rod 30.

Referring next to the matter of increased facilities for shifting the tally-roll carriage

into and out of printing position at will, I secure to the base of the machine at the righthand side a bracket 90 (Figs. 1 and 5) which has an upright portion and an inclined cross-head, to the lower part of which is pivoted a lever 91. This lever works over a flattened forward portion of the bracket and extends out beyond the front of the machine where it is equipped with a handle 91^a. In rear of its pivot the lever extends back to the righthand end of the rod 30 and has a bifurcated end embracing a roller stud 87^a on the aforesaid collar or sleeve 87. The said lever is a somewhat elongated piece of flat metal of angular form (Fig. 5) extending alongside the machine below the operating handle thereof and it supplies a very convenient means whereby the operator at will may shift the tally-roll carriage into and out of printing position. When this manual control of the tally-roll equipment is in use it is desirable that the spring 80 shall be for the time virtually put out of commission. I therefore arrange not only for preventing the carriage from being accidentally shifted from its non-printing position, but through the same agencies I provide for its being detained in printing position when shifted to that position by the said hand lever. The before mentioned arm 86 is secured to the boss of a sleeve 86^a, (Fig. 8) which has a drive fit in the bore of the adjacent stationary lug 31 so as to constitute a fixed support for a friction latch for engaging and detaining the rod 30 and consequently the whole tally-roll carriage. This friction latch is in the form of a blade 100 pivoted to the said arm 86 (Figs. 7 and 8) and connected by a spring 101 with a stud on a downward extension of said arm, which spring is adapted to cross the pivot of the latch when the latter is thrown back and forth in order that it may serve to hold the same in operative or inoperative position. In Fig. 7 it is shown out of operative position and in Fig. 8 it is shown in section in operative position and in Fig. 1 it is shown in dotted lines in operative position. When thrown to inoperative position it is limited by abutment of a tail 100^a against the stud to which the lower end of the spring 101 is attached. The blade is V-shaped in cross section on its under edge and adapted to frictionally engage V-shaped notches 30^a and 30^b in the rod 30. When engaged with the notch 30^a this latch holds the tally-roll carriage in printing position, the friction being sufficient to prevent the spring 80 from returning the carriage to non-printing position. When the carriage is in non-printing position and the blade or latch is in action it engages the other notch 30^b and prevents accidental displacement of the tally-roll carriage. When the latter is to be used in a co-operative relationship with 130

the tabulating mechanism of the main paper carriage, then the said latch or blade is preferably thrown to its ineffective position shown in Fig. 7, so that the spring may 5 serve to automatically return the tally-roll carriage to non-printing position.

Referring next to the use of the tally-roll equipment as an automatic adjunct to the tabulating equipment, the latter is in the 10 main the familiar one of the character disclosed in the beforementioned prior patents. It comprises a stop plate 105 (Fig. 2) mounted on the back panel 2 of the machine, and a rock rod 106 extending between the side plates of the carriage 19 and carrying a number of adjustable fingers 107 to coöperate with said stop plate for determining various columnar positions of the carriage. Said rock rod is both manually 15 and automatically operable as usual,—manually through the medium of a finger lever 108 (Fig. 1) applied to a crank arm 109 on the rod, and automatically through coöperation with elements of the line-spacing mechanism. The latter comprises the familiar cam 121 and lever 122 whose rear arm operates upon the bifurcated ear of a plate 110 sliding vertically upon the back panel of the machine and having lugs 110^a which 20 underlie the cross-rod 111 of a line-spacing bail which comprises arms 112 secured to a rock shaft 113. The latter has the usual connections with pawl-and-ratchet mechanism applied to the roller platen. Said bail 25 cross-rod 111 is embraced by jaws 115^b of another vertically sliding plate 115 which is mounted against the plate 110 and is operated in unison with it or not according as line-spacing is to occur or not. The coupling and uncoupling devices between these 30 plates is of familiar character comprising a dog or pawl 116 (Fig. 2) pivoted to the plate 110 and adapted to engage over a flange 115^a of plate 115 under the action of a spring 117. The fingers 107 are of two 35 different lengths which determine whether or not line-spacing will occur when the carriage is in the columnar position fixed by abutment of the finger against the shoulder 40 of the stop plate 105. Thus a finger of the greater length will operate upon the said dog or pawl and hold it away from the flange 115^a, whereas a finger of the shorter length will miss the dog or pawl. The latter, besides serving as a coupler between the two vertical plates, also serves the familiar function of rocking the rod 106 by acting upwardly against the longer stop fingers when the plate 110 rises. The main 45 carriage is spring-drawn to the left (as viewed from the front of the machine) as usual through the medium of a tape or band 114 (Fig. 9) and spring drum 114^a.

For the purpose of effecting automatic co- 50 operation between such tabulating mecha-

nism and the tally-roll carriage, the rock rod 106 carries one or more additional fingers 120 extending downward therefrom instead of forward as do the fingers 107. In the present instance two of these fingers 120 55 are shown and a special construction of tappet piece on the tally-roll carriage, whereby provision is made for bringing the latter into printing position for two different columnar positions of the main carriage 70 while at the same time providing for the return of the main carriage from the second of such tabular positions without being obstructed by the tally-roll carriage. To this end a tappet blade 130 is hinged to a plate 131 which is fastened to the side plate 34 of the lower tally-roll holder, and a spring 132 (Fig. 1) is applied to the hinge to hold the blade 130 against said side plate 34 so that an upwardly projecting rear portion 80 130^a of said blade above the side plate 34 will stand in the path of the fingers 120 as illustrated in Fig. 1. When the main paper carriage shifts to a certain columnar position for which one of these fingers 120 has 85 been set, that finger will strike against said upwardly projecting portion of the tappet blade and the tally-roll carriage will be carried along with the main paper carriage and brought to printing position. When 90 thereafter the rock rod 106 is operated, either manually or automatically as before described, the said finger 120 will be swung out of line with the upwardly projecting portion 130^a of the tappet blade, so that the 95 main paper carriage may move on to the next columnar position and the tally-roll carriage may return to its non-printing position. However, in this or some subsequent shift of the main paper carriage over 100 to another columnar position, for which the second finger 120 has been set, this finger will operate against the tappet blade, in the same way that the first finger did, and again move the tally-roll carriage into printing 105 position, as illustrated in Fig. 11. Upon the return of the carriage from this farther columnar position the first finger 120 is permitted to pass by the tappet blade by reason of the hinge-mounting of the same, 110 which action is illustrated in Fig. 12. It will, however, be understood that the pass-by character of the tappet device is useful whether one or more than one special finger 115 is used on the rock rod for bringing the tally 120 strip into printing position. Thus when only a single one of these fingers is employed it would not necessarily come into play upon shifting of the main paper carriage to its last columnar position, but of course might come into play in shift of that carriage to some intermediate columnar position beyond which the carriage would move in a subsequent operation of the machine, carrying the single finger 120 beyond 125 130

the tally-roll tappet piece. In fact various situations may arise which will call into play this pass-by character of the tappet device. For example it may be that the operator will desire to move the main carriage over to a certain columnar position for which a finger 120 has been set but without having that finger take the tally-roll carriage along, with the result that such finger would move over to a position beyond the tappet piece. In the latter connection it will be noted that the machine is so designed that the user may at will employ it for single column work in any columnar position of the carriage while at the same time having the tally-roll equipment available for the collection of any items that he may desire to select from the list for purposes of subsequent checking over of the work. To adapt the machine for this sort of use the automatic tabulating mechanism should of course be disabled and the line-spacing plates 110 and 115 kept coupled together. In the present instance a special key 140 is arranged at the righthand side of the keyboard (Figs. 1 and 5) and operates to disable the dog or pawl 116 and render effective a second coupling device 145 for the plates, not subject to displacement by a tabulator finger 107. Thus said key operates a thrust bar 142 extending across the back of the machine, which bar has a nose 142^a to act against an upward extension 116^b of said dog or pawl 116 so as to hold the latter out of position for rocking the rod 106, and said thrust bar has an upwardly projecting finger 142^b for interlocking the coupler piece 145 with the plate 115. Said coupler piece 145 is pivoted to the plate 110 and normally held by a spring 146 out of engagement with the plate 115, as shown in Fig. 2. The latter plate has a notch 115^c in one side and the coupler piece has a lug 145^c to engage said notch, as illustrated in Fig. 3. The connections between the thrust bar 142 and the key 140 comprise a lever 147 pivoted to the inner side of the back panel 2 (Fig. 1 and dotted lines Fig. 3) and having an inclined slot 147^a at its upper end engaged by a stud 148 on a laterally turned portion of a vertically movable horizontal bar 148 to which the stem 140^a of the key 140 is coupled, as shown in Fig. 1. Said key stem is permitted a slight rocking movement in order that it may be latched down in the familiar way, to wit, by engaging a notch with the upper keyboard plate. It will be understood that when this key is used the tally-roll friction latch 100 will preferably be set so that the shifting of the tally-roll carriage will be entirely controlled by the hand lever 91.

The tally strip 40 may, and preferably is, carbonized on the rear side for the purpose of manifolding upon the paper in the main

carriage though of course a supplemental ink ribbon might be employed for such purpose, if preferred. The aforesaid Main patent and a later Main application No. 862,294 filed September 18, 1914, both exemplify such an arrangement in which one feed connection serves for both tally strip and ink ribbon. I have shown a similar feed connection without the ink ribbon equipment, which connection comprises a ratchet wheel 150 on the take-up roller 36, and a spring-held actuating pawl 151 on a plate-lever 152 pivoting about the journal rod 35 of said roller and having a laterally projecting stud 153 adapted to be acted upon by the before-mentioned feed-lever 122 of the regular line-spacing mechanism of the machine proper. Normally said stud stands off clear of said lever as shown in Fig. 2 but when the tally-roll carriage is shifted into printing position the stud moves under the lever as shown in Fig. 3.

I claim:

1. In a machine of the class described, the combination with the printing mechanism of the machine proper, and the paper holder thereof mounted at its rear portion; of a supplemental paper holder shiftable relative to the main paper holder, and a hand lever coupled at its rear end to said supplemental holder and extending forwardly along the machine proper and having a handle at its front end.

2. In a machine of the class described, the combination with the printing mechanism of the machine proper, and the paper holder thereof mounted at its rear portion; of a supplemental paper holder shiftable relative to the main paper holder, a hand lever coupled at its rear end to said supplemental holder and extending forwardly along the machine proper and having a handle at its front end, and a friction latch for detaining the said holder in either of its two positions.

3. In a machine of the class described, the combination with the printing mechanism of the machine proper, and the paper holder thereof mounted at its rear portion and laterally shiftable; of a supplemental paper holder laterally shiftable relative to the main paper holder between pre-defined positions in and out of juxtaposition to the printing mechanism; means for shifting it into printing position by the main paper holder; and a hand lever for shifting it independently thereof.

4. In a machine of the class described, the combination with the printing mechanism of the machine proper, and the paper holder thereof mounted at its rear portion and laterally shiftable; of a supplemental paper holder laterally shiftable relative to the main paper holder between pre-defined positions in and out of juxtaposition to the

3
printing mechanism; means for shifting it into printing position by the main paper holder; a spring for returning it to non-printing position; a hand lever for moving said supplemental holder into printing position independently of movement of the main paper holder; and means for disabling said spring.

5. In a machine of the class described, the combination with the printing mechanism of the machine proper, and the paper holder thereof mounted at its rear portion and laterally shiftable; of a supplemental paper holder laterally shiftable relative to the main paper holder between pre-defined positions in and out of juxtaposition to the printing mechanism; means for shifting it into printing position by the main paper holder; a spring for returning it to non-printing position; a hand lever for moving said supplemental holder into printing position independently of movement of the main paper holder; and a friction latch for holding the same in such position.

20

25. 6. The combination with the printing mechanism of the machine proper and the main paper carriage thereof; of a laterally shiftable supplemental paper carriage com-

prising upper and lower roll holders and a connecting upright of rigid character accommodated between the main paper carriage and the printing mechanism. 30

7. The combination with the printing mechanism of the machine proper and the main paper carriage thereof; of a laterally shiftable supplemental paper carriage comprising upper and lower roll holders and a connecting plate with a vertical chute occupying space between the main paper carriage and the printing mechanism. 35

8. The combination with the printing mechanism of the machine proper and the main paper carriage thereof and its roller platen; of a laterally shiftable supplemental paper carriage comprising roll holders above and below said platen and a connecting plate occupying space between the printing mechanism and the main paper carriage and extending past the roller platen and being apertured to accommodate the type of 40 50 said printing mechanism.

CHARLES A. LUNDGREN.
